TYPEWRITING MACHINE

William A. Dobson, Wethersfield, Conn., assignor
to Underwood Elliott Fisher Company, New
York, N. Y., a corporation of Delaware

Application December 30, 1938, Serial No. 248,504

3 Claims. (Cl. 197—143)

This invention relates generally to the platen carriage structures of typewriting machines and has reference particularly to the paper shelf thereof and associated mechanisms.

One of the objects of the invention is to provide an improved paper shelf and associated carriage structure, affording a neat and practical arrangement of improved appearance, as well as being adapted for economic manufacture in an attractive, durable structure.

Another object is to provide an improved mounting for the paper shelf on the platen carriage to facilitate swinging of the shelf to or from its normal position by a momentary, carefree finger-touch, to thus afford convenient access to a carriage stop or like mechanism housed by the paper shelf and normally concealed thereby.

A further object is to provide an improved arrangement of paper shelf and associated typewriter carriage, the latter presenting a generally low, shallow structure and having carriage stop devices carried thereby, the paper shelf reaching well above the carriage to afford adequate support of the paper and blending with the low carriage in a manner to form a complete cover therewith, concealing the stop devices, and lending a shallow, yet rugged appearance to the typewriter.

The present invention also relates to improvements in paper shelf and associated carriage structures, over my prior Patent No. 2,126,315, issued August 9, 1938.

Other objects and advantages will hereinafter appear.

In the drawing.

Figure 1 is a perspective view of the typewriter platen carriage and associated paper shelf embodying my improvements, portions being broken away to reveal inner mechanism.

Figure 2 is a fragmentary perspective view of the paper shelf end portion partly broken away to facilitate illustration.

Figure 3 is an enlarged detail sectional view taken on line 3—3 of Figure 4, illustrating one end portion of the paper shelf and carriage.

Figure 4 is a transverse sectional view taken on the line 4—4 of Figure 3, and

Figure 5 is a view similar to Figure 4 but illustrating the paper shelf swung to low position for access to the carriage stop mechanism.

The embodiment of the invention herein illustrated forms part of the Underwood typewriting machine of the portable or light-duty class. A platen carriage includes end members or plates

7 in which a rotatable platen 8 is journaled, the latter being manually rotated for paper feeding

by a platen knob 9, and in line-space rotation by the usual mechanism including a ratchet wheel 10. Each carriage end plate 7 has an inturned flange 11 along the top edge thereof and a back flange 12 inturned at the rear edge thereof to reinforce the end-plate structure and afford a neat, compact appearance to the carriage, the top flange 11 being substantially horizontal and at a low elevation of the carriage. To facilitate feeding of the paper onto the platen 8, the usual paper deflector 13 is provided, as shown more clearly in Figure 4, this deflector having a rolled edge 14 to strengthen same longitudinally and provide a mounting for the paper deflector 13 on studs 15 carried on the respective end plates 7. 5 10 15

The platen carriage is movable transversely on the typewriter during line typing, and the various carriage positions, determining the line-lengths or margins and line-indenting, are controlled by the usual margin and tabulator stop mechanism 20 which may include a rack bar 17 secured at its respective ends by brackets 18 to each carriage end plate 7. The rack bar 17 is adapted to adjustably carry suitable margin stops 19 and tabulator stops 20 arranged to cooperate with suitable counter-stops not shown, in determining the several typing positions. 25

A paper shelf, generally indicated by numeral 21, is adapted for fabrication of Bakelite or other molded material, as by a die-casting process, and 30 is swingably mounted on the carriage in position relative to the platen to serve mainly as a paper rest and is disposed normally to overlie and conceal the stop rack bar 17. The paper shelf 21 comprises mainly, a front wall 22 inclining forwardly and downwardly to meet the paper deflector 13 in abutting relation therewith, and a rear wall or apron 23 which is disposed, in the normal position of the paper shelf, to lie substantially flush with the back flanges 12 of each carriage end plate 7 and abut same, see Figure 4. 35

The shelf walls 22 and 23 meet at an apex 24 which is well rounded to enhance the appearance of the typewriter and to provide a surface receding gradually rearwardly from the front wall 22 to form an appropriate rest for the typing paper overhanging from the platen 8. To reinforce the paper shelf 21 a plurality of intermediate webs 25, and webs 26 adjacent each end of the paper shelf 21, inter-connect the walls 22, 23 thereof. 40 45

The paper shelf 21 further includes end walls 27 which depend from the rounded apex 24 and meet the top flanges 11 of the carriage end plates 7. 50

It will thus be seen that the structure of the paper shelf 21, including the front and rear walls 55

22, 23 and the end walls 27, provides an enclosure completely covering the carriage stop mechanism, particularly the rack bar 17 thereof, to conceal same from view and to afford the practical advantage of preventing the deposit of dust or erasure particles on this mechanism. It will also be seen that the structure of the paper shelf as described, comprising the several outer walls and connecting webs, is particularly adapted for fabrication of a molded or Bakelite material, and in organization with the generally shallow carriage structure, forms a rugged, neat arrangement, although affording a paper shelf of adequate area. The usual paper side edge guide 28 is adjustably carried on the paper shelf 21, being suitably held in adjusted position thereon to guide the paper in feeding same to the platen 8.

The paper shelf 21 is swingable from its normal position, Figure 4, to that shown in Figure 5 to thus afford access to the stop mechanism, particularly for adjusting the desired positions of the stops 19, 20 on the rack bar 17. Each end wall 27 includes an ear 29 having an aperture journaling a pivot pin 30 threadably carried in a block 31 secured to each end plate 7, constituting the pivotal mounting for the paper shelf 21.

It is desired that the paper shelf 21 be swung to either position with facility, requiring merely a momentary finger touch to bring the paper shelf to the desired position. To accomplish this, an overthrow spring 32 is operatively carried on coacting studs 33, 34, each stud having a reduced end portion forming a groove and a terminal head, in which groove the respective looped ends 35 of the spring 32 are engaged, the spring 32 being initially compressed to urge the studs 33, 34 further apart from each other in either position of the paper shelf, as indicated by the arrow in Figures 4 and 5. Stud 33 is stationary and is accordingly carried on a fixed member of the platen carriage, herein the end plate 7. Stud 34 is movable with the paper shelf and is held on the lower portion of the end web 26. It will be seen that the shelf-carried, movable stud 34, in either 45 position of the paper shelf, is positioned to either side of a center line passing through the pivot pin 30 and the stationary stud 33, and that as stud 34, during swinging of the paper shelf, passes this center line in either direction, the force of spring 32 overthrows stud 34 and thereby fully actuates the paper shelf to the desired position. Thus, the manual force exerted on the paper shelf need only swing the shelf until its stud 34 is slightly beyond this center line, whence 50 the force of the overthrow spring 32 actuates the shelf the remaining distance until same is detented by suitable stops.

The normal position of the paper shelf 21, is defined by the engagement of a cushion 35 of yieldable material such as felt, secured to an edge of the end wall 27, with the stud 33 as shown in Figure 4. The Figure 5 position of the paper shelf is determined preferably by the action of a link 36 coacting with the studs 33, 34, the link 36 having elongate slots 37, 38 riding on the reduced end portions of the respective studs 33, 34. The portion of link 36 defining the slot 37 is arcuate so that the link may move in a region within the limits of the carriage end plate flange 11 and the paper shelf rear wall 23. Although a single spring overthrow device at one end of the paper shelf would suffice, it is preferred to employ a similar such device at each shelf end so as to avoid subjecting the shelf to any undue twisting stress in swinging same.

It may be here noted that the structure and association of the overthrow spring 32 and link 36 facilitate the assembly of these parts with the studs 33, 34. The slots 37, 38 in the link are each of a width adequate to permit installing the link on the studs by threading same over each head thereof, the link being held in an angular position relative to the axis of each stud to permit the stud head to pass through the slot. After being so installed, the position of link 36 at right angles to the axes of the studs 33, 34 is maintained by the close association of the spring 32 with the link in such manner as to crowd link 36 to one end of the reduced stud portions and against the shoulders bordering the grooves thereof. It will, of course, be noted that the compression of spring 32 holds the looped spring ends onto the respective studs, although these end loops are open to permit easy assembly. This association of spring 32 and link 36 with the studs 33, 34 also has advantage in repair or maintenance of the typewriter in facilitating the removal of the paper shelf 21, it being only required, after dismantling the spring and link, to withdraw the pivot pins 30 to complete the removal.

Although in this application, there is specifically described, one embodiment which the invention may assume in practice, it will be understood that same is shown for the purposes of illustration, and that the invention may be modified and embodied in various other forms without departing from its spirit or the scope of the appended claims.

What is claimed is:

1. In a typewriting machine, in combination, a platen carriage having a carriage stop mechanism carried thereby, a paper shelf swingably mounted on said carriage in position to normally overlie and conceal said stop mechanism and swingable rearwardly to ineffective position to reveal said stop mechanism, a first stud carried on said carriage and a second stud on said paper shelf, an overthrow spring operatively connected with said studs and effective, upon swinging said shelf to an intermediate position, to actuate said shelf to either position, and a link having slots riding on said studs and limiting the rearward swinging of said paper shelf.

2. In a typewriting machine, in combination, a platen carriage having a carriage stop mechanism carried thereby, a paper shelf swingably mounted on said carriage in position to normally overlie and conceal said stop mechanism and swingable rearwardly to ineffective position to reveal said stop mechanism, a first stud carried on said carriage and a second stud on said paper shelf, each of said studs having a peripheral groove, an overthrow spring presenting a looped wire form having hooked ends seating in said stud grooves and effective, upon swinging said shelf to an intermediate position, to actuate said shelf to either of said positions, and a link having slots riding in the grooves of said studs to limit the rearward swinging of said paper shelf.

3. In a typewriting machine, in combination, a platen carriage having a carriage stop mechanism carried thereby, a paper shelf swingably mounted on said carriage in position to normally overlie and conceal said stop mechanism and swingable rearwardly to ineffective position to reveal said stop mechanism, a first stud on said carriage and a second stud on said paper shelf, each of said studs having a peripheral groove adjacent the stud end, an overthrow spring presenting a looped

wire form having hooked ends seating in said stud grooves and effective, upon swinging said shelf to an intermediate position to actuate said shelf to either of said positions, and a link having slots in said link permitting passage of the stud ends therethrough to facilitate assembly, said spring retaining said link in operative position on said studs.

5 riding in the grooves of said studs to limit the rearward swinging of said paper shelf, the slots
